START-STOP PRINTER ADAPTATION TO
SYNCHRONOUS MULTIPLEX TELEGRAPHYRichard E. Mathes, Westfield, N. J., assignor to
Radio Corporation of America, a corporation
of Delaware

Application September 3, 1937, Serial No. 162,280

8 Claims. (Cl. 178—52)

This invention relates to printing telegraph systems and more particularly to devices whereby start-stop printers may be actuated over synchronous multiplex radio channels.

5 Radio communications systems have been commonly used for multiplex telegraphy, using various forms of code signalling, including Morse code, and the so-called five-unit printing code. Printers which are adapted for synchronous operation in response to five-unit code signals are of one type. An adaptation of synchronous multiplex telegraphy to the requirements of radio communications is disclosed in my pending application Serial No. 101,204, filed September 17, 15 10, 1936, which was assigned to the assignee of this application. A somewhat similar adaptation is disclosed in U. S. Patent No. 2,160,463, granted May 30, 1939, to James A. Spencer.

There is another type of printers known as 20 start-stop printers which respond usually to signals having seven elements of which one is a start element, five of which are the code selecting elements and the last of which is the stop element. It is an object of my invention to provide a synchronous multiplex system adapted to operate a start-stop printer.

It is another object of my invention to provide a communications system for use particularly on radio channels wherein the signalling 30 time is successively assigned to different channels and the repetition of assignments thereto is at a rate sufficient to allot the time to each channel successively and once during the time interval ordinarily allotted to the unit time element 35 of a code signal. Thus, for example, if a code signal for a start-stop system consists of seven elemental time units, and if the system is adapted to transmit three messages simultaneously, then each channel will successively occupy the signalling time once for every time unit of the signal code. For three code signals transmitted by 40 the three operating position stations of a multiplex system there are twenty-one elemental time units, or bauds as they are called; that is, 45 seven bauds per code signal.

The novelty which I believe to reside in my improved arrangement as herein disclosed resides fundamentally in the adaptation of a start-stop printer system to synchronous multiplex transmission channels. Ordinarily, as has been known in the past, a start-stop system was used only in 50 simplex circuits, although, of course, it is well known how to adapt a simplex system of any type to certain forms of duplexing.

55 Bearing in mind the fundamental objects of

my invention, as above mentioned, other objects and advantages will presently become apparent as the detailed description thereof is set forth.

In the following description reference will be made to the accompanying drawing, in which

Figure 1 shows diagrammatically the essential elements of construction which go to make up the system as a whole, and Fig. 2 is a diagram showing how the transmitting time is allotted successively to different channels so as to permit of 10 interweaving the elements of different code signals. It will be understood, however, that this drawing discloses only one preferred embodiment and that variations from that embodiment 15 may readily suggest themselves to those skilled in the art.

Referring to the drawing, I show a drive motor 1, the speed of which is controlled from some convenient synchronizing source or constant speed vibrator. This motor drives a pole-changing commutator 2 whereby direct current of opposing polarities may be impelled into a power amplifier circuit 3. This amplifier 3 has an output circuit through which is delivered an alternating current of substantially sine wave formation for driving a synchronous motor 4. Other power amplifiers and associated synchronous motors are preferably operated at the same time with operating units 3 and 4 when traffic is to be maintained on the different multiplex channels. In a three-channel multiplex system it is customary to dispose three brushes 24 at 60° angles about the periphery of the pole-changing commutator 2, one for each of three power-amplifiers 3. For the sake of simplicity the details 35 of construction appropriate to only one channel have been shown in the drawing.

The phasing of each synchronous motor 4 with respect to the others of the multiplex system is readily accomplished with the aid of a stroboscope or its equivalent of any preferred type. Such a stroboscope is here shown as constituted by a neon lamp 5 in front of which is a rotating disc 6 having an opening 7 therein for observing the position of the disc at the instants when the 40 neon lamp 5 is ignited. The device for transmitting impulses to the lamp 5 has not been fully shown in the drawing as it forms no essential part of the invention. It will suffice to state that once during each revolution of the commutator 2 50 a short sharp impulse having like polarity on both output leads from the amplifier produces a potential drop across the transformer 25 and thus lights the lamp 5 for a brief moment. Thus the phasing of the synchronous motor 4 may be 55

observed by its fixed relation to the position of the disc opening 7 when the neon lamp 5 is ignited. The proper phase relations between the different motors 4 are then maintained in accordance with the 60° displacements between the three brushes 24.

The interlacing of the elemental units of code signals of the different multiplex channels is represented diagrammatically in Fig. 2. In this figure the signalling time allotted to each channel is shown by the elements 8. It will be seen that the time normally allotted to a code element of the ordinary start-stop simplex system is here divided into three smaller units in order that three separate communications may be transmitted as by multiplex methods over three channels simultaneously.

The drive motor 1 is shown conventionally as connected to a multiplex distributor 8, as well as to the afore-mentioned pole-changing commutator 2. The multiplex distributor receives plus or minus impulses on each of its segments for keying a radio transmitter 9. Each code signal, as initiated by a tape transmitter 10, usually consists of seven elements, the first of which may be considered a marking element if there is no code signal available to be transmitted, and a spacing element if the start impulse is to be transmitted. This start impulse is then followed by the selecting code having five units of either plus or minus polarity according to the permutational arrangement necessary for transmitting a given character. The five-unit selecting code is then followed by a stop impulse as the seventh unit of the signal.

The tape transmitter device 10 may be of any well known type such that the code selection can take place within the period of time taken up by one revolution of the commutator brush 11 over the segments of a distributor indicated generally at 12. This distributor may be of the face plate type as shown, or in place thereof a set of cam-actuated contact springs may be substituted. In either case the commutator 12 is actuated by the synchronous motor 4. During one revolution of the brush 11 seven revolutions of the brush 23 are necessary (according to the arrangement shown in the drawing) in order to obtain the transmission of a given code signal as set up by the keyboard or tape transmitter 10. Other tape transmitters B and C will ordinarily be feeding signals through their appropriate commutators (like 12) to different segments of the multiplex distributor 8. The elemental portions of the signals are, therefore, interlaced. If desired, the R. P. M. of the brush 23 may be reduced by duplicating the segments on the distributor plate 8.

In the commutator 12 the segment allotted to the start impulse is shown at 13. The five segments for the selecting code are designated *a*, *b*, *c*, *d* and *e*, respectively, and the stop segment is designated 14. Since a positive marking impulse can be adopted for the stop unit of the code signal, the segment 14 is shown connected to the positive side of the source 15.

Each code selecting operation of the transmitter 10 is initiated by a movement of the transfer switch 26 from engagement with a positively polarized contact to a contact through which the collector ring 27 and the channel selecting segment 28 are interconnected. If the perforated tape is temporarily arrested, then segment 28 is continuously fed with marking bias potential. As shown in the aforementioned Spencer U. S. Patent 2,160,463, the sensing of tape perforations

by the pecker pins on the transmitter is suitably timed in relation to the commutator cycles so that no incomplete code signals can be transmitted.

The code-forming switches of the device 10 are conventionally shown with marking contacts on the right connected to the positive side of the source 15 and with spacing contacts on the left connected to the negative side of the source 15. Other details of the device 10 are well known in the art and it is unnecessary to make further disclosure of such details in this application, since they form no part of the invention.

It will be understood, of course, that by means of suitable gear ratios between the motors and the drive shaft connections to each rotary unit, the correct timing of the different commutator brushes in relation to each other will be maintained.

Various forms of tape controlled transmitters are known (and their use is herein contemplated) in which the tape itself determines whether or not the feeding device shall remain in operation or shall be stopped. The above mentioned U. S. Patent 2,160,463 shows one example of such a tape feeding device. The amount of slack in the tape between the transmitter and the tape perforator determines the starting and stopping of the transmitter. Despite the starting and stopping of the tape feed, however, it will be understood that the commutator 12 runs continuously, and that if no signals are fed thereto by the transmitter then the transfer switch remains in position to keep the segment 28 biased with marking potential. On the channel in question, therefore, the receiving printer at the other end of the communications channel will remain inactive. In all respects, therefore, the receiving printer is enabled to function in the same manner as is customary for operation on a simplex start-stop printer channel.

In order to complete the disclosure of my invention I have shown a radio transmitter 9 feeding signals to an antenna 17 from which energy may be radiated to the receiving antenna 18 and utilized thereat in the control of the radio receiver 19. The output signals from the receiver 19 may be fed to a receiving multiplex distributor 20 having as many segments 21 thereon as there are channels to be multiplexed. Each of the segments 21 feeds signals to an appropriate start-stop printer A', B' and C'. The multiplex distributor 20 is preferably driven by a synchronous motor 22, current for which is obtained in the same manner as shown for equivalent synchronous motors 4 at the transmitting station. In this case, however, it is necessary to derive from the signals themselves the synchronizing impulses for maintaining the proper speed of the master drive motor at the receiving station corresponding to the drive motor 1 at the transmitter. This method of synchronizing is well known in the art and need not be further dwelt upon in this disclosure.

In the operation of my invention it will now be seen that at the transmitting end the perforated tape is scanned by the pecker pins, which mechanically actuate switches of one type or another for impressing plus and minus impulses simultaneously upon the various segments *a* to *e* inclusive of the distributor 12. These pecker-pin-controlled circuits are then scanned through the medium of the distributor and the resulting impulses are applied to the line through the multiplex distributor 8. The various units of each code signal are transmitted sequentially and

of uniform duration and each start-stop signal of one channel is interwoven with corresponding start-stop signals of the remaining channels in the multiplex system. At the receiving end a 5 multiplex receiving distributor is maintained in synchronism with the multiplex transmitting distributor so that the signals are all distributed at the proper speed and phase for actuating different start-stop printers A', B' and C' each 10 appropriate to a different channel.

I claim:

1. In a multiplex printing telegraph system a speed-governed motor, a multiplex channel-time allotment commutator operable by said motor, a plurality of printing telegraph transmitting distributors each having time-division positions for each element of a start-stop code signal, additional motors each for individually driving one of said distributors, synchronizing means operable from the first said motor for controlling the speed of said additional motors, means for fixing the speed ratio between said commutator and said distributors, also the mutual phase relationships between the several distributors, thereby 15 to obtain successive channel-time allotments for each element of the respective code signals to be transmitted, independent means appropriate to each multiplex channel for feeding code signals to one of said distributors, a plurality of 20 start-stop printers respectively operable by signals on each multiplex channel, and means synchronized by said signals for maintaining the proper distribution of said signals to said printers.

2. A system according to claim 1 and further characterized in that the last said means includes a multiplex channel-time receiving commutator operable in synchronism with the first said commutator.

3. Apparatus for transmitting time division multiplex signals for control of start-stop printers comprising a channel time allotment commutator and a plurality of code-element distributors, means including appropriate code signal keying devices for feeding start-stop character-signals to each of said distributors, connections from each distributor to respectively different positions on said commutator, individual synchronous motors for driving each of said distributors respectively, and means controlled by the speed of said commutator for regulating the 10 frequency of the alternating current fed to said motors.

4. Apparatus according to claim 3 and including means for maintaining constant phase displacements between respective ones of said distributors while permitting each of said keying devices to be started and stopped independently.

5. In a system for simultaneously operating a plurality of start-stop telegraph printers over a single time-division multiplex communications channel, the method of signaling which comprises dividing the signaling time into unitary elements successive ones of which are utilizable for the operation of different printers, each unitary element constituting an aliquot part of a character code signal, causing independent keying operations to be made for the transmission of equal

length character code signals appropriate to each printer, and causing the unitary elements of said code signals to be interlaced when transmitted over said channel.

6. In a system for simultaneously operating a plurality of start-stop telegraph printers over a single time-division multiplex communications channel, the method of signaling which comprises dividing the signal time into unitary elements successive ones of which are utilizable for the 10 operation of different printers, causing different communications to be independently translated into start-stop character code signals of equal length, causing said unitary time elements to be appropriated individually and in 15 rotation by different portions of different code signals, thereby to interlace the units of said code signals, and causing the units of each code signal, when received, to be segregated for control of a character printing operation on one of 20 said printers, respectively.

7. In a time division multiplex telegraph system, a perforated tape transmitter adapted to control the composition of 5-unit printing telegraph code signals, a commutator having seven time-division positions one of which corresponds with a start unit, five of which cover the units of a 5-unit code signal, and the seventh of which corresponds with a stop unit of a 7-unit start-stop code signal, means for impressing marking 30 and spacing bias potentials on the several positions of said commutator under control of said perforated tape transmitter, means for interlacing the elemental portions of the code signals of different channels in said multiplex system, a 35 synchronously controlled channel time distributor located at a receiving station in said system, a start-stop printer at said receiving station, and means operative in accordance with the distribution of code signals by said distributor at said receiving station to respectively different channels of the multiplex system for causing said start-stop printer to print the intelligence represented by said 7-unit start-stop code signals.

8. In a time division multiplex telegraph system having synchronously controlled distributors at the transmitting and receiving stations respectively, the method of utilizing start-stop printer code signals on at least one of the multiplex channels, which comprises scanning at the transmitting station a 5-unit code record, translating the effects of the scanning operation into a sequence of code impulses of permutationally arranged marking and spacing biases, prefacing each code signal by a start signal of spacing bias, sufficing each code signal by a stop signal of marking bias, interlacing the seven units, including start, code and stop units, of signals pertaining to one channel with signal units of different channels in the multiplex system, allocating the 7-unit code signals thus formed and transmitted to an appropriate time division multiplex channel, and causing intelligence to be printed at the receiving station in accordance with the significance of said 7-unit code signals. 45 50 55 60 65
